COMPARTMENTED SILVERWARE TRAY

Merwin A. Caine, R.F.D. 1, Box 218,
Jackson, N.J. 08527

Filed May 3, 1967, Ser. No. 6,929

Term of patent 14 years

(Cl. D9—242)

FIG. 1

FIG. 2

FIG. 3

FIG. 4

FIG. 5

FIG. 1 is a front perspective view of a compartmented silverware tray, showing my new design;
 FIG. 2 is a side elevational view thereof;
 FIG. 3 is a top plan view thereof;
 FIG. 4 is a front elevational view thereof; and
 FIG. 5 is a rear elevational view thereof.

I claim:

The ornamental design for a compartmented silverware tray, as shown.
